CLAIM

The ornamental design for a trolley bag, as shown and described.

DESCRIPTION

FIG. 1 is a rear, right, and top perspective view of a trolley bag, showing my new design;

FIG. 2 is a front, left, and bottom perspective view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a perspective view thereof, illustrated in another configuration; and,

FIG. 10 is a perspective view thereof, illustrated in an additional configuration.

The broken lines in the drawings depict portions of the

trolley bag that form no part of the claimed design.
